(57) **CLAIM**

The ornamental design for a fishing reel portion, as shown and described.

DESCRIPTION

FIG. 1 is a perspective view of a fishing reel with a fishing reel portion in accordance with our new design;

FIG. 2 is a first side elevational view of the fishing reel with the fishing reel portion illustrated in FIG. 1;

FIG. 3 is a second side elevational view of the fishing reel portion illustrated in FIG. 1;

FIG. 4 is a top plan view of the fishing reel with the fishing reel portion illustrated in FIG. 1;

FIG. 5 is a bottom plan view of the fishing reel with the fishing reel portion illustrated in FIG. 1;

FIG. 6 is a first end elevational view of the fishing reel with the fishing reel portion illustrated in FIG. 1;

FIG. 7 is a second end elevational view of the fishing reel with the fishing reel portion illustrated in FIG. 1;

FIG. 8 is another perspective view, similar to FIG. 1, of the fishing reel with the fishing reel portion illustrated in FIG. 1, but with an operating part being moved to an alternate position;

FIG. 9 is still another perspective view of the fishing reel with the fishing reel portion illustrated in FIG. 1, but with the operating part being moved to the alternate position as illustrated in FIG. 8;

FIG. 10 is still yet another perspective view of the fishing reel with the fishing reel portion illustrated in FIG. 1, but with the operating part being moved to the alternate position as illustrated in FIGS. 8 and 9;

FIG. 11 is still yet another perspective view of the fishing reel with the fishing reel portion illustrated in FIG. 1, but with the operating part being moved to the alternate position as illustrated in FIGS. 8 to 10;

FIG. 12 is an enlarged perspective view of the fishing reel portion illustrated in FIG. 9; and,

FIG. 13 is an enlarged perspective view of the fishing reel portion illustrated in FIG. 10.

The broken line illustration of the environmental structure (the remaining structure of the fishing reel) in the drawings is not part of the claimed design.
